STEAM BOILER

Karl C. Schmidt, Western Springs, Ill., assignor
to The Babcock & Wilcox Company, Newark,
N. J., a corporation of New Jersey

Application April 13, 1935, Serial No. 16,115

20 Claims. (Cl. 122—235)

My present invention relates to the construction and operation of water tube boilers and more particularly to steam boilers adapted for industrial and marine installation having limited 5 head room and floor space.

The main object of my invention is the provision of a steam boiler of the type described which is further characterized by the relatively large amount of convection and radiant heat 10 absorbing surface, furnace volume, length of heating gas travel and steam collecting space provided in proportion to the total space occupied and head room required, its relatively low cost of construction, and its ease of assembly and 15 erection.

The various features of novelty which characterize my invention are pointed out with particularity in the claims annexed to and forming a part of this specification. For a better understanding of the invention, its operating advantages and specific objects attained by its use, 20 reference should be had to the accompanying drawings and descriptive matter in which I have illustrated and described preferred embodiments 25 of my invention.

Of the drawings:

Fig. 1 is a transverse vertical section of a steam boiler constructed in accordance with my invention taken on the line 1—1 of Fig. 2;

Fig. 2 is a longitudinal vertical section taken on the line 2—2 of Fig. 1;

Fig. 3 is a horizontal section taken on the line 3—3 of Fig. 2;

Fig. 4 is a partial longitudinal vertical section taken on the line 4—4 of Fig. 1;

Fig. 5 is a horizontal section through the dry drum taken on the line 5—5 of Fig. 1; and

Fig. 6 is a view similar to Fig. 1 illustrating a modification.

The steam boiler unit illustrated in Figs. 1 to 5 comprises a setting or housing substantially rectangular in horizontal and vertical cross-sections, and formed by a front wall 10, rear wall 11, side walls 12 and 13, a top wall or roof 14, and bottom 45 wall or floor 15. The side, end, and top walls are advantageously formed, as shown, by an outer steel casing 16, an inner layer of insulating material 17, and a fire brick lining 18. Extending upwardly along the side walls are I-beams 19 which support girders 20 extending across the 50 top of the setting.

The interior of the setting is divided as hereinafter described into a relatively wide central combustion lane 21 and a pair of relatively narrow laterally adjoining heating lanes 22 at oppo-

site sides thereof. A pair of horizontally disposed substantially parallel upper and lower drums 23 and 24 respectively extend longitudinally and throughout the length of each heating lane and are connected throughout their length by a bank 5 of substantially straight vertically disposed tubes 25 having bent ends radially connected into the drums at both sides of the vertical plane including the longitudinal axes of the drums. The drums 23 and 24 are advantageously of small 10 diameter to present the necessary amount of surface for the tube bank connections while minimizing the head room requirements and weight of the drums. The upper drums 23 are supported from the girders 20 as indicated, and 15 in turn support the lower drums 24 through the tube banks 25.

Each heating lane is separated from the adjoining combustion lane except at the rear end thereof by a vertically disposed refractory partition 26 which extends between the drums 23 and 24 and terminates at its rear end a substantial distance from the rear wall 11. Each drum 24 is protected along its lower inner section by a refractory curb 27 extending along the floor 15. 20 The space between the opposite side of each lower drum and the adjacent side wall is closed by refractory material, so that the gases in the heating lanes are substantially confined to the space therein between the drums 23 and 24. A 25 heating gas outlet or stack connection 28 controlled by a damper 29 is provided at the front end of each heating lane. With this arrangement heating gases generated in the combustion lane will divide at the rear end thereof between 30 the two heating lanes and flow forwardly therein 35 between the drums to the outlets 28.

The steam boiler illustrated is especially designed for the burning of a fluid fuel, such as oil, gas or pulverized fuel, in suspension. An oil 40 burner 30 is conventionally shown as mounted in a burner port 31 centrally formed in the front wall 10 and arranged to discharge a stream of fuel horizontally into and towards the rear end of the combustion lane. The front end of the 45 combustion lane is formed by a refractory faced ignition section having a flat refractory arch 32 and a pair of rearwardly flaring refractory side walls 33 to facilitate ignition of the entering fuel and to reflect and radiate heat towards the 50 portion of the combustion lane at the rear thereof.

The portion of each tube bank laterally adjoining the ignition section of the combustion lane is utilized as an economizer section. As 55

shown in Figs. 1 and 4, the three foremost rows of tubes 25 have their upper ends enclosed by a pan or box 34 to which feed water is supplied, and the lower drum 24 is divided by a partition 35 into a short front compartment and a long rear compartment. With this arrangement the feed water will pass downwardly through the tubes communicating with the pan 34, and then upwardly through the remaining tubes in front 10 of the drum partition 35. The feed water then distributes along the remaining portion of the tube bank, some of the tubes acting as down-comers and others as risers.

The section of the combustion lane between the 15 rear end of the ignition section and the rear end of the partition 26 is normally the main combustion zone and is surrounded by radiant heat absorbing surface. As shown, oppositely arranged intersecting rows of substantially L-shaped water tubes 36 extend transversely of the combustion lane, each having one leg 36^a connected to a corresponding lower drum and inclined across the bottom of the combustion lane and a second vertical leg 36^b extending upwardly 20 along and partly supporting the opposite partition 26 with the upper end of the vertical leg connected into the opposite upper drum 23. The horizontally disposed legs of the two rows of tubes 36 intersect at approximately the middle of the 25 bottom of the combustion lane, as shown in Fig. 1. The tubes in the two rows alternate, so that adjacent tube legs are substantially in contact at the plane of intersection, as shown in Fig. 2, and form a water screen with progressively increasing vertical spacing between adjacent tube 30 legs towards the sides of the combustion lane. The spaces along the inner sides of the partitions between the tube legs 36^b are occupied by additional oppositely arranged alternating rows of L-shaped water tubes 37. Each of the tubes 37 has the lower end of its vertical leg 37^b connected to one of the drums 24 and extending upwardly along the corresponding partition 26 between the legs 36^b of the tubes 36 and its second 35 leg 37^a extending at an inclination across the top of the combustion lane and connected to the opposite upper drum 23. The inclined legs 37^a of adjacent tubes 37 intersect along approximately the middle of the combustion lane, and are arranged to support the top wall of the setting. The rows of tubes 36 terminate at the rear end of the partition, but the row of tubes 37 on which the roof is supported extend to the rear wall 11, as shown in Figs. 2 and 3. The tubes 36 and 37 40 are more closely spaced longitudinally than the tubes 25, but the spacing between adjacent tubes 37 is greater than between the tubes 25 so that the tube legs 37^b beyond the rear end of the partition form in effect a slag screen for the tubes 25 at the rear end of the tube banks. By this arrangement of the combustion lane tubes 36 and 37, a fluid circulation is provided between the two pairs of drums and tube banks so that common 45 pressure and water level conditions will be maintained in both sections of the boiler. Uniform operating conditions are further insured by an equalizer tube 38, as shown in Figs. 2 and 3, extending between the rear ends of the lower drums 24, and bent to accommodate any expansion 50 stresses that may occur in operation. An access door 39 is provided at the floor level in the front wall 10.

In operation with this arrangement of the parts, most of the steam will be generated in the 55 radiant heat absorbing tubes 36 and 37 and in the

rear section of the tube banks. A steam outlet connection 40 is provided at the front or economizer end of each drum 23 in view of the relatively quiescent conditions in that section. A splash plate 41, having a rearwardly curved upper end 5 extends across each drum 23 at the rear end of the economizer section to insure non-turbulent conditions in the economizer sections. A longitudinally extending perforated dry pipe 42 is located in the economizer end of the drum above 10 the water level therein and connected to the corresponding steam outlet 40.

A dry drum 50 is arranged above and extending transversely of the forward ends of the drums 23, with its opposite ends connected to the steam 15 outlets 40. The dry drum contains a relatively wide inclined channel plate 51 at each end thereof directly in the path of the wet steam from the outlet connections 40, causing the steam to change direction around the sides of the channel and the 20 moisture impinging on and adhering to the plate to drop into the bottom of the dry drum. The dry drum is provided with drain connections 52 leading to and sealed in the adjacent upper drum 23. The steam outlet 53 from the dry drum is advantageously arranged to extend horizontally from the upper central portion thereof to further reduce the head room requirements of the unit.

As shown in Fig. 4, a vertically extending baffle 55 is positioned in the upper portion of 30 each heating lane transversely of the economizer section of the tube bank to cause the forwardly flowing stream of heating gases to bend around the lower end of the baffle and avoid short-circuiting of the lower portions of the tubes at 35 the forward end of the tube bank.

The modified construction shown in Fig. 6 is especially designed for marine installations, differing mainly from the construction shown in Figs. 1 to 5 by the absence of the tube connections between the spaced tube banks and drums. In this construction, the tubes 36 and 37 of the combustion lane are replaced by two oppositely arranged rows of continuous U-shaped tubes 60, having oppositely inclined top and bottom legs 45 60^a and 60^b respectively connected to upper and lower drums at the same side of the boiler and intermediate vertical legs 60^c extending along the inner side of the opposite partition. The opposite rows of U-shaped tubes have their corresponding 50 legs 60^a and 60^b intersecting along the vertical axial plane of the combustion lane. The spaces between the vertical legs 60^c along the partitions 26 are occupied by vertically disposed tubes 61 extending between corresponding upper and lower 55 drums.

While in accordance with the provisions of the statutes I have illustrated and described preferred embodiments of my invention, those skilled in the art will understand that changes may be 60 made in the form of the apparatus disclosed without departing from the spirit of the invention covered by my claims, and that certain features of my invention may sometimes be used to advantage without a corresponding use of other 65 features.

I claim:

1. A steam boiler having a pair of substantially parallel horizontally disposed upper and lower drums, a bank of vertically disposed water tubes 70 extending between and connected to said drums along the length thereof, means forming a longitudinally extending combustion lane and a heating lane laterally adjoining said combustion lane and containing said tube bank, a row of substan- 75

tially L-shaped water tubes extending transversely of said combustion lane each having one leg connected to said lower drum and extending along the bottom of said combustion lane and the second leg along the side opposite said tube bank, a second row of substantially L-shaped water tubes extending transversely of said combustion lane each having one leg connected to said lower drum and extending along said tube bank and the second leg extending across the top side thereof, a longitudinally extending drum connected to the upper ends of both of said rows of L-shaped tubes, and means for burning fuel in said combustion lane and generating heating gases flowing longitudinally thereof and thence through said heating lane.

2. A steam boiler having a pair of substantially parallel horizontally disposed upper and lower drums, a bank of substantially straight vertically disposed water tubes extending between and connected to said drums along the length thereof and disposed at both sides of the plane including the longitudinal axes of said drums, means forming a longitudinally extending combustion lane arranged substantially wholly at one side of said axial plane and a heating lane laterally adjoining said combustion lane and containing said tube bank, said heating lane receiving heating gases solely from and communicating with said combustion lane only at one end thereof, said means including a vertically disposed longitudinally extending partition separating and forming one side of said combustion and heating lanes, a row of substantially L-shaped water tubes extending transversely of said combustion lane each having one leg connected to said lower drum and extending along the bottom of said combustion lane and the second leg along the side opposite said tube bank, a second row of substantially L-shaped water tubes extending transversely of said combustion lane each having one leg connected to said lower drum and extending along said partition and the second leg extending across the top side of said combustion lane, a longitudinally extending drum connected to the upper ends of both of said rows of L-shaped tubes, and means at the opposite end of said combustion lane for burning fuel therein and generating heating gases flowing longitudinally through said combustion lane and thence through said heating lane.

3. A steam boiler having a pair of substantially parallel horizontally disposed upper and lower drums, a bank of vertically disposed water tubes extending between and connected to said drums along the length thereof, means forming a longitudinally extending combustion lane and a heating lane laterally adjoining said combustion lane and containing said tube bank and communicating with said combustion lane at one end thereof, said means including a vertically disposed longitudinally extending partition separating and forming one side of said combustion and heating lanes, a row of substantially L-shaped water tubes extending transversely of said combustion lane each having one leg connected to said lower drum and extending along the bottom of said combustion lane and the second leg along the side opposite said tube bank, a second row of substantially L-shaped water tubes extending transversely of said combustion lane each having one leg connected to said lower drum and extending along said partition and the second leg extending across the top side of said combustion lane, a longitudinally extending drum connected to the

upper ends of both of said rows of L-shaped tubes, and means at the opposite end of said combustion lane for burning fuel therein and generating heating gases flowing longitudinally through said combustion lane and thence through said heating lane.

4. A steam boiler having horizontally spaced pairs of substantially parallel horizontally disposed upper and lower drums, a bank of vertically disposed water tubes extending between and connected to each pair of drums along the length thereof, means forming a longitudinally extending combustion lane and heating lanes laterally adjoining said combustion lane, each of said heating lanes containing one of said tube banks and communicating with said combustion lane at one end thereof, oppositely arranged intersecting rows of substantially L-shaped water tubes extending transversely of said combustion lane each having one leg connected to one of said lower drums and extending laterally along the bottom of said combustion lane and the second leg upwardly along the opposite side thereof, the upper end of each of said L-shaped tubes being connected to the opposite upper drum, and means at the opposite end of said combustion lane for burning fuel therein and generating heating gases flowing longitudinally through said combustion lane and thence through said heating lanes.

5. A steam boiler having horizontally spaced pairs of substantially parallel horizontally disposed upper and lower drums, a bank of vertically disposed water tubes extending between and connected to each pair of drums along the length thereof, means forming a longitudinally extending combustion lane and heating lanes laterally adjoining said combustion lane, each of said heating lanes containing one of said tube banks and communicating with said combustion lane at one end thereof, oppositely arranged intersecting rows of substantially L-shaped water tubes extending transversely of said combustion lane each having one leg connected to one of said lower drums and extending laterally along the bottom of said combustion lane and the second leg upwardly along the opposite side thereof, the upper end of each of said L-shaped tubes being connected to the opposite upper drum, and means at the opposite end of said combustion lane for burning fuel therein and generating heating gases flowing longitudinally through said combustion lane and thence through said heating lanes.

6. A steam boiler having horizontally spaced pairs of substantially parallel horizontally disposed upper and lower drums, a bank of vertically disposed water tubes extending between and connected to each pair of drums along the length thereof, means forming a longitudinally extending combustion lane and heating lanes laterally adjoining said combustion lane, each of said heating lanes containing one of said tube banks and communicating with said combustion lane only at one end thereof, said means including vertically disposed longitudinally extending partitions separating said combustion lane from said heating lanes, oppositely arranged intersecting rows of substantially L-shaped water tubes extending transversely of said combustion lane beyond the end of said partitions and each having one leg connected to one of said lower drums and extending upwardly along the corresponding side of said combustion lane and the second leg laterally along and supporting the roof of said

combustion lane, the upper end of each of said L-shaped tubes being connected to the opposite upper drum, and means at the opposite end of said combustion lane for burning fuel therein and generating heating gases flowing longitudinally through said combustion lane and thence through said heating lanes.

7. A steam boiler having horizontally spaced pairs of substantially parallel horizontally disposed upper and lower drums, a bank of vertically disposed water tubes extending between and connected to each pair of drums along the length thereof, means forming a longitudinally extending combustion lane and heating lanes laterally adjoining said combustion lane, each of said heating lanes containing one of said tube banks and communicating with said combustion lane at one end thereof, oppositely arranged intersecting rows of substantially L-shaped water tubes extending transversely of said combustion lane each having one leg connected to one of said lower drums and extending laterally along the bottom of said combustion lane and the second leg upwardly along the opposite side thereof, additional oppositely arranged intersecting rows of substantially L-shaped water tubes extending transversely of said combustion lane each having one leg connected to one of said lower drums and extending upwardly along the corresponding side of said combustion lane and the second leg laterally along the roof of said combustion lane, the upper end of each of said L-shaped tubes being connected to the opposite upper drum, and means at the opposite end of said combustion lane for burning fuel therein and generating heating gases flowing longitudinally through said combustion lane and thence through said heating lanes.

8. A steam boiler having horizontally spaced pairs of substantially parallel horizontally disposed upper and lower drums, a bank of vertically disposed water tubes extending between and connected to each pair of drums along the length thereof, means forming a longitudinally extending combustion lane and heating lanes laterally adjoining said combustion lane, each of said heating lanes containing one of said tube banks and communicating with said combustion lane only at one end thereof, said means including vertically disposed longitudinally extending partitions separating said combustion lane from said heating lanes, oppositely arranged intersecting rows of substantially L-shaped water tubes extending transversely of said combustion lane each having one leg connected to one of said lower drums and extending laterally along the bottom of said combustion lane and the second leg upwardly along the opposite side thereof, additional oppositely arranged intersecting rows of substantially L-shaped water tubes extending transversely of said combustion lane each having one leg connected to one of said lower drums and extending upwardly along the corresponding partition and the second leg laterally along the roof of said combustion lane, the upper end of each of said L-shaped tubes being connected to the opposite upper drum, and means at the opposite end of said combustion lane for burning fuel therein and generating heating gases flowing longitudinally through said combustion lane and reversely through said heating lanes.

9. A steam boiler having horizontally spaced pairs of substantially parallel horizontally disposed upper and lower drums, a bank of sub-

stantially straight vertically disposed water tubes extending between and connected to each pair of drums along the length thereof and disposed at both sides of the plane including the longitudinal axes of said drums, means forming a longitudinally extending combustion lane and heating lanes laterally adjoining said combustion lane, each of said heating lanes containing one of said tube banks, said heating lanes receiving heating gases solely from and communicating with said combustion lane only at one end thereof, said means including vertically disposed longitudinally extending partitions separating said combustion lane from said heating lanes, oppositely arranged intersecting rows of substantially L-shaped water tubes extending transversely of said combustion lane each having one leg connected to one of said lower drums and extending laterally along the bottom of said combustion lane and the second leg upwardly along the opposite side thereof, additional oppositely arranged intersecting rows of substantially L-shaped water tubes extending transversely of said combustion lane each having one leg connected to one of said lower drums and extending upwardly along the corresponding partition and the second leg laterally along the roof of said combustion lane, the upper end of each of said L-shaped tubes being connected to the opposite upper drum, and means at the opposite end of said combustion lane for burning fuel therein and generating heating gases flowing longitudinally through said combustion lane and reversely through said heating lanes.

10. A steam boiler having horizontally spaced pairs of horizontally disposed upper and lower drums, a bank of water tubes extending between and connected to each pair of drums along the length thereof, means defining a combustion chamber between and extending longitudinally of said tube banks, said means including oppositely arranged rows of bent water tubes extending transversely of said combustion chamber, each of said bent tubes having one leg connected to one of said lower drums and extending laterally across the lower portion of said combustion chamber and a second leg upwardly along the opposite side of said combustion chamber, the upper end of each of said bent tubes being connected to one of said upper drums.

11. A steam boiler having horizontally spaced pairs of horizontally disposed upper and lower drums, a bank of water tubes extending between and connected to each pair of drums along the length thereof, means defining a combustion chamber between and extending longitudinally of said tube banks, said means including oppositely arranged rows of substantially L-shaped water tubes extending transversely of said combustion chamber, each of said L-shaped tubes having one leg connected to one of said lower drums and extending laterally across the lower portion of said combustion chamber and its second leg upwardly along the opposite side of said combustion chamber, the upper end of each of said L-shaped tubes being connected to the opposite upper drum.

12. A steam boiler having horizontally spaced pairs of horizontally disposed upper and lower drums, a bank of water tubes extending between and connected to each pair of drums along the length thereof, means defining a combustion chamber between and extending longitudinally of said tube banks, said means including oppositely arranged rows of substantially L-shaped

water tubes extending transversely of said combustion chamber, each of said L-shaped tubes having an inclined leg connected to one of said lower drums and extending laterally across the lower portion of said combustion chamber and intersecting the axial plane of the inclined legs of the oppositely arranged L-shaped tubes and its second leg extending upwardly along the opposite side of said combustion chamber, the upper end of each of said L-shaped tubes being connected to the opposite upper drum, and means for burning fuel in suspension in said combustion chamber above said inclined tube legs.

15. A steam boiler having horizontally spaced pairs of substantially parallel horizontally disposed upper and lower drums, a bank of vertically disposed water tubes extending between and connected to each pair of drums along the length thereof, means forming a longitudinally extending combustion lane and heating lanes at opposite sides of said combustion lane, each of said heating lanes containing one of said tube banks and communicating with said combustion lane at one end thereof, oppositely arranged intersecting rows of bent water tubes extending transversely of said combustion lane, each of said bent tubes having one leg connected to one of said lower drums and extending laterally across the lower portion of said combustion lane and a second leg upwardly along the opposite side thereof and connected to one of said upper drums, and means at the opposite end of said combustion lane for burning fuel therein and generating heating gases flowing longitudinally through said combustion lane and thence through said heating lanes.

40. A steam boiler having horizontally spaced pairs of horizontally disposed upper and lower drums, a bank of vertically disposed water tubes extending between and connected to each pair of drums along the length thereof, means defining a combustion chamber between and extending longitudinally of said tube banks, said means including oppositely arranged rows of bent water tubes extending transversely of said combustion chamber between upper and lower drums and including oppositely inclined tube legs connected to said lower drums and extending laterally across the lower portion of said combustion chamber, vertical tube legs extending upwardly along opposite sides of said combustion chamber, and oppositely inclined tube legs connected to said upper drums and extending laterally across the upper portion of said combustion chamber, and means for burning fuel in suspension in said combustion chamber.

55. A steam boiler having horizontally spaced pairs of substantially parallel horizontally disposed upper and lower drums, a bank of vertically disposed water tubes extending between and connected to each pair of drums along the length thereof, means forming a longitudinally extending combustion lane and heating lanes at opposite sides of said combustion lane, each of said heating lanes containing one of said tube banks communicating with said combustion lane at one end thereof, oppositely arranged rows of bent water tubes extending transversely of said combustion lane between upper and lower drums and including oppositely inclined tube legs connected to said lower drums and extending laterally across the lower portion of said combustion lane, vertical tube legs extending upwardly

along opposite sides of said combustion lane, and oppositely inclined tube legs connected to said upper drums and extending laterally across the upper portion of said combustion lane, and means at the opposite end of said combustion lane for burning fuel therein and generating heating gases longitudinally through said combustion lane.

16. A steam boiler having horizontally spaced pairs of horizontally disposed upper and lower drums, a bank of water tubes extending between and connected to each pair of drums along the length thereof, means defining a combustion chamber between and extending longitudinally of said tube banks, said means including oppositely arranged rows of substantially L-shaped water tubes extending transversely of said combustion chamber, each of said L-shaped tubes having one leg connected to one of said lower drums and extending laterally across the lower portion of said combustion chamber and its second leg upwardly along the opposite side thereof, additional oppositely arranged rows of substantially L-shaped water tubes extending transversely of said combustion chamber, each of said additional L-shaped tubes having one leg connected to one of said lower drums and extending upwardly along the corresponding side of said combustion chamber and its second leg laterally across the upper portion of said combustion chamber, the upper end of each of said L-shaped tubes being connected to the corresponding opposite upper drum.

17. A steam boiler having horizontally spaced pairs of horizontally disposed upper and lower drums, a bank of vertically disposed water tubes extending between and connected to each pair of drums along the length thereof, means forming partitions separating a longitudinally extending combustion lane from heating lanes at opposite sides of said combustion lane, each of said heating lanes containing one of said tube banks and opening to said combustion lane beyond one end of said partitions, oppositely arranged rows of substantially L-shaped water tubes extending transversely of said combustion lane beyond the end of said partitions and each having one leg connected to one of said lower drums and extending upwardly along the corresponding side of said combustion lane and spaced from adjacent L-shaped tubes to form a slag screen across the entrance to each of said heating lanes and its second leg extending across the upper portion of said combustion lane and connected to the opposite upper drum, and means for burning fuel in said combustion lane and generating heating gases flowing longitudinally through said combustion lane and thence through said heating lanes.

60. 18. A steam boiler comprising a horizontally disposed upper drum, a substantially parallel laterally spaced lower drum, means defining a horizontally elongated combustion chamber in the space between and extending longitudinally of said drums, said means including oppositely arranged groups of substantially L-shaped water tubes extending transversely of said combustion chamber, the L-shaped tubes in one of said groups having one leg connected to said lower drum and extending laterally across the lower portion of said combustion chamber and a second leg upwardly along the opposite side thereof, the L-shaped tubes in the other of said groups having one leg connected to said lower drum and ex-

- tending upwardly along the corresponding side of said combustion chamber and a second leg laterally across the upper portion of said combustion chamber, the upper end of each of said L-shaped tubes being connected to said upper drum, and means at one end of said combustion chamber for burning fuel and generating a horizontal flow of heating gases longitudinally therethrough.
- 10 19. A steam boiler comprising a horizontally disposed upper drum, a substantially parallel laterally spaced lower drum, means defining a horizontally elongated combustion chamber in the space between and extending longitudinally of said drums, said means including oppositely arranged rows of substantially L-shaped water tubes extending transversely of said combustion chamber, the L-shaped tubes in one of said rows having one leg connected to said lower drum and extending laterally across the lower portion of said combustion chamber and a second leg upwardly along the opposite side thereof, the L-shaped tubes in the other of said rows having one leg connected to said lower drum and extending upwardly along the corresponding side of said combustion chamber and its second leg laterally across the upper portion of said combustion chamber, the upper end of each of said L-shaped tubes being connected to said upper drum, a bank of steam generating tubes directly connected into said upper drum, means including a partition defining a heating lane containing said tube bank and separating the combustion chamber and heating lane, and means for burning fuel in said combustion chamber and

generating a horizontal flow of heating gases longitudinally therethrough and subsequently through said heating lane.

20. A steam boiler comprising a horizontally disposed upper drum, a substantially parallel laterally spaced lower drum, means defining a horizontally elongated combustion chamber in the space between and extending longitudinally of said drums, said means including oppositely arranged groups of substantially L-shaped water tubes extending transversely of said combustion chamber, the L-shaped tubes in one of said groups having one leg connected to said lower drum and extending laterally across the lower portion of said combustion chamber and a second leg upwardly along the opposite side thereof, the L-shaped tubes in the other of said groups having one leg connected to said lower drum and extending upwardly along the corresponding side of said combustion chamber and its second leg laterally across the upper portion of said combustion chamber, the upper end of each of said L-shaped tubes being connected to said upper drum, a vertical bank of steam generating tubes directly connected into one of said drums and arranged along one side of said combustion chamber, means including a vertical partition defining a heating lane containing said vertical tube bank and separating the combustion chamber and heating lane, and means at one end of said combustion chamber for burning fuel and generating a horizontal flow of heating gases longitudinally therethrough and subsequently through said heating lane.

KARL C. SCHMIDT. 35
